CLAIM

We claim, the ornamental design for a metal detector, as shown and described.

DESCRIPTION

FIG. 1 is a perspective view drawing of a metal detector according to an embodiment of the design.

FIG. 2 is a side view drawing of a metal detector according to an embodiment of the design.

FIG. 3 is a user end view drawing of a metal detector according to an embodiment of the design.

FIG. 4 is a search coil end view drawing of a metal detector according to an embodiment of the design.

FIG. 5 is a top view drawing of a metal detector according to an embodiment of the design.

FIG. 6 is a side view drawing of a metal detector according to an embodiment of the design.

FIG. 7 is a bottom view drawing of a metal detector according to an embodiment of the design.

FIG. 8 is a perspective view drawing of a metal detector according to an embodiment of the design.

FIG. 9 is a perspective view drawing of a metal detector according to an embodiment of the design.

FIG. 10 is a perspective view drawing of a metal detector according to an embodiment of the design.

FIG. 11 is a perspective view drawing of a metal detector according to an embodiment of the design, and which illustrates a detector coil in broken line that is not a part of the claimed design.

FIG. 12 is a perspective view drawing of a metal detector according to an embodiment of the design.

FIG. 13 is a perspective view drawing of a metal detector according to an embodiment of the design, and which illustrates a detector coil in broken line that is not a part of the claimed design; and,

FIG. 14 is a perspective view drawing of a metal detector according to an embodiment of the design.

A portion of the several drawing figures illustrate a search coil, in broken line, attached to the claimed metal detector. The purpose of the broken line search coil is to illustrate an application of the metal detector, and the broken line search

(Continued)

coil portion of the drawing figures do not form a part of the presently claimed metal detector.
